UNITED STATES PATENT OFFICE

101,524

DESIGN FOR AN ILLUMINATED ALTAR

John Frei, Jr., Chicago, Ill.

Application August 5, 1936, Serial No. 64,257

Term of patent 14 years

To all whom it may concern:

Be it known that I, John Frei, Jr., a citizen of the United States, residing at Chicago, in the county of Cook, and State of Illinois, have invented a new, original, and ornamental Design for an Illuminated Altar, of which the following is a specification, reference being had to the accompanying drawing, forming a part thereof.

The figure is a perspective view of an illuminated altar showing my new design.

I claim:

The ornamental design for an illuminated altar, as shown.

JOHN FREI, JR.
